UNITED STATES PATENT OFFICE.

GLENN D. HERTZLER, OF LOS ANGELES, CALIFORNIA.

FOUNTAIN-PEN AND PENCIL CLIP.

1,248,115.

Specification of Letters Patent.

Patented Nov. 27, 1917.

Application filed January 11, 1917. Serial No. 141,811.

To all whom it may concern:

Be it known that I, GLENN D. HERTZLER, a citizen of the United States, residing at Los Angeles, in the county of Los Angeles and State of California, have invented new and useful Improvements in Fountain-Pen and Pencil Clips, of which the following is a specification.

This invention relates to a pen and pencil holder and particularly pertains to a clip adapted to be attached to the clothing in a manner to safely secure pencils and pens therein.

It is the principal object of this invention to provide a pen and pencil holder which may be securely fastened within a pocket or upon the clothing of the wearer and will afford a grip within which several pens and pencils may be simultaneously held.

Another object of this invention is to provide a clip which may be easily fastened in position and which will thereafter hold pens and pencils in a manner to permit their ready removal when desired.

It is a further object of this invention to provide a pen and pencil holder which is simple in its construction and inexpensive, both as to manufacture and to material.

30 Other objects will appear hereinafter.

The invention is illustrated, by way of example, in the accompanying drawings in which:

Figure 1 is a view in side elevation illustrating a fragmentary portion of a vest showing the pocket therefor and a pen and pencils secured by the clip therein.

Fig. 2 is a view in section and elevation as seen on the line 2-2 of Fig. 1 and illustrates the manner in which various articles may be accommodated within the holder, as well as the combined fastener and grip therefor.

Fig. 3 is a view in perspective illustrating the holder as disassociated from a mounting.

Fig. 4 is a view in plan elevation illustrating the modified form of the invention in which the compartments of the holder are lined with material which will prevent the articles from slipping therefrom.

Referring more particularly to the drawings, 10 indicates a holder which is here shown in the formation of a safety pin having a back 11. This back is formed with a series of arcuate recesses 12, 13 and 14. The recesses 12 and 13 are positioned at the

opposite ends of the back and are of a size to correspond to the diameter of pencils in general use. The recess 14 is disposed between the first named recesses and is of a larger size to receive fountain pens and other articles of like dimension. The back is formed of a piece of rigid material which is flat and of a width which will provide sufficient friction surfaces for the gripping of the articles. One end of the back is reduced in width to form a pin 15 which is constructed with a coil 16 adapted to provide it with resilience. This pin extends substantially parallel to the back and registers with a catch or eye 17 formed by the opposite end of the back member. It will be understood that this eye may be of any desired configuration and that it will perform the same results obtained by a safety pin in preventing accidental removal of the pin from register therewith.

Reference being had to Fig. 4 it will be seen that the clip here shown is identical with the one shown in the preceding figures. This construction, however, embodies a friction lining member 18 of rubber or fabric which will prevent the pencils and pens from slipping from the holder.

In operation the holder is pinned at any convenient point upon the clothing and as here shown is positioned within a pocket. When a pencil is placed therein it will register with one of the recesses 12 or 13 and, due to its diameter, will force the pin outwardly and cause the pencil to be securely gripped within the recesses by the back member and the pin. The removal of the pencil may be effected by merely drawing it from the holder, after which the holder will be in condition to again receive it without further adjustment or arrangement.

It will thus be seen that the device here disclosed is simple in construction, may be easily operated and will positively grip a pen or pencil in position and permit its being readily removed therefrom.

While I have shown the preferred form of my pen and pencil holder as now known to me, it is evident that various changes may be made in the combination, construction and arrangement of parts by those skilled in the art without departing from the spirit of my invention.

I claim:

1. A pen and pencil clip comprising a

rigid bar having arcuate recesses extending from its inner face, a spring coil formed integral with one end of the bar, a pin formed integral with one end of the coil, and an eye formed integral with the other end of the bar and adapted to receive the point of the pin.

2. A pen and pencil clip comprising a rigid bar having arcuate recesses extending from its inner face, a spring coil formed integral with one end of the bar, a pin formed integral with one end of the coil, an eye formed integral with the other end of the bar and adapted to receive the point of the pin, and a frictional lining in said recesses; so that when the clip is placed in a pocket and the pin inserted through the material of the back side of the pocket the

recesses will hold a pen or pencil by frictional engagement between the lining of the bar, the pin, and the material of the pocket.

3. A pen and pencil clip comprising a rigid bar having arcuate recesses extending from its inner face, a pin attached to one end thereof and an eye formed at the other end of said bar and adapted to receive the point of the pin, the pin being substantially in the same plane as said bar and adapted, when inserted through a textile fabric, to hold the pen or pencil by frictional engagement between said fabric and said recesses.

In testimony whereof I have signed my name to this specification.

GLENN D. HERTZLER.

Copies of this patent may be obtained for five cents each, by addressing the "Commissioner of Patents, Washington, D. C."
